UNITED STATES PATENT OFFICE

CECELIA H. COHEN, OF BROOKLYN, NEW YORK

SAMPLE DISPLAY TAB

Application filed January 9, 1930. Serial No. 419,629.

This invention relates to improvements in sample display tabs and to the method of making the same.

Heretofore, it has been the practice in mounting sample fabrics upon cards or tabs, to wrap the material around the card and adhesively secure the fabric thereto. This necessitates the mounting of the fabric on individual cards requiring considerable labor and time as well as a waste of material as the same is applied so as to cover one side of the card with the edges folded back and secured against the rear side. It is, therefore, the primary object of my invention to expedite the manufacture of such sample tabs at a low cost of material and labor.

Another object of the invention is to provide a new method of mounting sample fabrics on insert tabs by providing a back mat against which the length of sample fabric is placed, then folding a mask having spaced windows therein over the mat and sample fabric, adhesively securing the meeting faces of said mask and mat together, and then cutting the strip or gang of tabs loose on a plane intermediate the window openings.

Another object of the invention is the provision of a sample fabric display tab in which the sample fabric is interposed or sandwiched between two layers of cardboard, one of which is provided with a window opening for displaying the color and texture of the sample material.

Another object of the invention is to provide a sample tab having insert tongues on opposite ends thereof, one of the end walls of the window opening being cut to a shape so that it co-acts with the walls of the slit or cutout of the mounting sheet to provide an attractive enclosure design for the display of the printed color name or stock or catalog number of the particular sample fabric supported thereon.

With these and other objects in view, the invention resides in a certain novel construction, combination and arrangement of parts, the essential features of which are herein-after fully described, are particularly pointed out in the appended claim and are illus-

trated in the accompanying drawings, in which:—

Figure 1 is a plan view of a gang of tabs before folding.

Figure 2 is a similar view showing the same in folded position.

Figure 3 is a vertical longitudinal sectional view on the line 3—3 of Figure 2.

Figure 4 is a perspective view of one of the display tabs per se.

Figure 5 is a horizontal sectional view on the line 5—5 of Figure 4.

Figure 6 is a fragmentary plan view of a mounting sheet for the tabs shown in Figure 4.

Figure 7 is a similar view but showing the tabs mounted upon the mounting sheet.

Figure 8 is a horizontal sectional view on the line 8—8 of Figure 7.

Figure 9 is a plan view of a slightly modified form showing a double gang of tabs before folding.

Figure 10 is a further modification showing the blank from which the tab is formed before folding.

Figure 11 is a horizontal sectional view of the form shown in Figure 10 in a folded position with a sample fabric secured therein.

Referring to the drawings by reference characters, the numeral 10 designates a back mat of cardboard or other like material which is cut to provide transversely disposed end tongues 11 and 12 along opposite sides thereof.

The mat 10 may be of any length depending of course upon the number of tabs to be cut from a single strip. Associated with the back mat 10 is a front mask 13, the longitudinal sides of which are provided with spaced opposed tongues 14 and 15, the latter tongues being joined to the tongues 12 of the mat 10 so that all of the tongues 11, 12, 14 and 15 are in horizontal alignment.

Both the mat 10 and the front mask 13 are constructed from a single blank of cardboard material cut in a single operation and are foldable one over the other on the scored or

folded lines 16 dividing the tongues 12 from the tongues 15. The mask 13 is provided with cutout openings or windows 17 in alignment with the respective opposed tongues.

Both the mat 10 and the front mask 13 are constructed from a single blank of cardboard material cut in a single operation and are foldable one over the other on the scored or

folded lines 16 dividing the tongues 12 from the tongues 15. The mask 13 is provided with cutout openings or windows 17 in alignment with the respective opposed tongues.

Both the mat 10 and the front mask 13 are constructed from a single blank of cardboard material cut in a single operation and are foldable one over the other on the scored or

14 and 15 and are shown as substantially rectangular in configuration, the end walls of the cutout openings adjacent the tongues 15 being of a shape to point inwardly for a purpose to be presently explained.

6 The opposite end of the back mat 10 and mask 13 terminate in cutoff flaps 18 for a purpose to be hereinafter appreciated. In 10 the drawings I have shown the inner surface of the mat 10 as provided with an adhesive substance 19 which when moistened will cause the inner faces of the back mask and mat to be secured together after the same have been folded on the scored line 16. In 15 the process of manufacturing the display tabs of the kind herein shown, a piece of sample fabric 20 of the kind to be displayed is placed lengthwise of the back mat 10, the gummed surface having first been moistened, after 20 which the gummed surface of the mask 13 is likewise moistened and the said mask folded on the fold line 16 so as to overlie the back mask, and when pressure is applied to the folded section, the aligned tongues 11 and 12 25 will register with the aligned tongues 14 and 15 of the mask, the adhesive bond between the mask and mat serving to hold the sample fabric 20 interposed or sandwiched there between. The gang of tabs now appear as 30 shown in Figure 2 with the sample fabric 20 displayed through the window openings 17 of the mask. The outer face of the front mask 13 is provided with cut lines or scored lines 21 intermediate the respective window 35 openings 17 and adjacent the end windows of the strip whereby to guide the cutting knife when the gang or strip of tabs is inserted in a cutting machine. By cutting the gang of tabs on the lines 21, the same become separated from the strip and form the completed tab T as shown in Figures 4 and 5 of the drawings. The end flaps 18 after the cutting operation are discarded but by cutting the same from the end tabs, the said end tabs appear 40 identical to the intermediate ones after the cutting operation.

45 The finished tab piece as shown in Figures 4 and 5 of the drawings, include a rear wall, a front wall having the window opening 17 50 therein and insert tongues formed by the registering tongues 11, 12, 14 and 15 and which will be referred to by the numerals 22 and 23. Printed adjacent the pointed end wall 24 of the window opening 17 is the stock number 55 and color of the sample material 20 and which is disposed so as not to be concealed when the tongue 22 is inserted into the slit or cutout opening in the mat on which the tab is to be mounted and which mat will now 60 be fully described.

65 In Figures 6 to 8 inclusive I have shown a cardboard or paper mat 25 which is provided with horizontal slit or cutout openings 26 and 27 respectively, the former being in the nature of a true triangle for the reception of the

insert tongue 22 of the tab piece, while the insert tongue 23 is inserted in the slit or cutout 70 27. When these tongues are inserted in the respective slits or cutout openings as shown in Figure 7 of the drawings, the printed matter or indicia 25 is visibly displayed and appears to be enclosed in a square border, the outline of which is formed by the pointed end wall 24 of the window opening and the right angle edges of the triangular slot 26 in the mounting mat 25. Although I have shown the so called enclosing border as 75 square in configuration, the end wall of the cutout opening 17 and the shape of the insert slot 26 may be varied if desired to form other styles. The inner ends of the insert tongues 22 and 23 terminate in vertical shoulders 28 which abut the walls of the insert slots 26 and 27 for limiting lateral shifting of the tabs when in mounted position.

80 From the foregoing description, it will be seen that any number of gangs or strips of tabs may be placed one upon the other in stack formation and cut in a single operation. This will effect a saving of both time, labor 85 and material.

85 In Figure 9 of the drawings the same idea is embodied as that hereinbefore described but in this form two mats 29 and 30 are arranged continuous to each other while integral with 90 the outer sides of the mat are masks 31 and 32, the said masks 31 and 32 being foldable over the respective mats 29 and 30, whereupon two strips of folded tabs may be formed in a single operation and likewise cut in a single 95 operation.

100 In Figures 10 and 11 I have shown a further modified form wherein the tab T' is constructed of two identical sections 33 and 34 having window openings 35 and 36 respectively provided therein, the insert tongues 37 and 38 of the respective sections being joined together but foldable on the line 39. The other ends of the sections 33 and 34 are provided with insert tongues 40 and 41 respectively. The inner surface of the tab section 33 is provided with a coating of gum or other adhesive substance 42 whereupon folding of the sections 33 and 34 one upon the other with a piece of sample fabric 43 interposed therebetween, will cause the said sections to become secured together with the fabric displayed on opposite sides of the tab proper T'. By providing a window opening 110 on opposite sides of the tab, a person may not only view the color of the particular fabric 115 but is permitted to feel the texture and quality of the same.

120 In the foregoing description I mentioned that a plurality of strips of tabs may be cut 125 in a single cutting operation with one strip arranged on top of another and by this same arrangement, a complete set of various color sample tabs may be cut out in the same operation and by arranging them in proper order, 130

they may be removed from the cutting machine for insertion into the mounting mats in the particular order desired. By the construction of tabs shown, a relatively thin and light structure is provided so that when mounted upon the mounting mats the same will not appear bulky and when so mounted they will appear uniform and provide a neat and attractive display.

10 While I have shown and described what I deem to be the most desirable embodiment of my invention, it is obvious that some of the details may be varied without in any way departing from the spirit of my invention 15 and I, therefore, do not limit myself to the exact details of construction herein set forth nor to anything less than the whole of my invention limited only by the appended claim.

20 Having thus described my invention what I claim as new and desire to secure by Letters Patent, is;

25 A sample display card comprising a pair of identical sections joined together at one end, 30 said section having window openings therein and being folded at the joined end one over the other for bringing the window openings in registration, a piece of sample fabric interposed between the folded sections, and means 35 for securing said folded sections together with the sample fabric secured therebetween.

In testimony whereof I affix my signature.
CECELIA H. COHEN.
